UNITED STATES PATENT OFFICE.

WILLIAM E. JAMES, OF PRICHARD, ALABAMA.

ICE-BOX.

1,234,766.

Specification of Letters Patent. Patented July 31, 1917.

Application filed June 10, 1916. Serial No. 102,947.

To all whom it may concern:

Be it known that I, WILLIAM E. JAMES, a citizen of the United States, residing at Prichard, in the county of Mobile and State 5 of Alabama, have invented certain new and useful Improvements in Ice-Boxes; and I do hereby declare the following to be a full, clear, and exact description of the invention, such as will enable others skilled in 10 the art to which it appertains to make and use the same.

This invention relates to improvements in an ice box and more particularly to the type for cooling and keeping cool bottles containing 15 beverages and one of its objects is the provision of a chamber divided into a plurality of compartments for supporting bottles one above the other in each compartment, whereby they will be kept cool by ice 20 within the ice chamber of the ice box.

Another object of this invention is to provide a door to each compartment, having means for gripping the lowermost bottle in the respective compartment to withdraw 25 said bottle upon opening the respective door, obviating the necessity of a person putting his hand within water which is contained in the compartment for cooling the contents of the bottle.

30 A further object of this invention is to provide a grab to each door for gripping the bottom of the lowermost bottle of each compartment to withdraw same from the compartment when the door thereof is 35 swung to an opened position.

A still further object of this invention is the provision of an ice box of the above stated character, which shall be simple, durable and efficient, and which may be manufactured and sold at a comparatively low 40 cost.

With these and other objects in view as will become more apparent as the description proceeds, the invention consists in certain 45 novel features of construction, combination and arrangement of parts as will be hereinafter more fully described and claimed.

For a complete understanding of my in-

vention, reference is to be had to the following description and accompanying drawing, in which:

Figure 1 is a front elevation of an ice box, constructed in accordance with my invention,

55 Fig. 2 is a transverse sectional view, taken on the line 2—2 of Fig. 1, and

Fig. 3 is a sectional view, taken on the line 3—3 of Fig. 2, illustrating a plurality of compartments.

60 Referring in detail to the drawing, the numeral 1 indicates as an entirety an ice box, consisting of a front wall 2, a rear wall 3, side walls 4, a top wall 5 and a bottom wall 6. A suitable perforated partition 7 is secured to the inner faces of the walls of the ice box to form an ice chamber between the same and the top wall 5. The front wall 2 adjacent the ice chamber is provided with a pair of openings which 65 are closed by doors 8, whereby the ice chamber may be supplied with ice. The front wall 2 of the ice box is provided with an opening 9, in which is mounted an inclined wall 10 which extends from a point out of 70 the ice box to a point within the ice box and has secured to its inner lower end an upwardly inclined rear wall 11 which is secured to a strip 12 carried by the rear wall 3 of the ice box, providing a storage 75 chamber. The storage chamber is divided into a plurality of compartments by vertically extending walls 13. The compartments of the storage chamber are adapted 80 to receive a plurality of bottles, one positioned upon the other as clearly illustrated in Fig. 2 and which are submerged within water received from the ice chamber, by the melting of the ice therein, or if desired the storage chamber may be filled with water 85 from any desired source.

90 A plurality of doors 14 are secured to the front wall adjacent the partition 7 upon the outer face thereof by hinges 15, having their lower ends resting against the outer end of 95 the inclined wall 10 of the storage chamber for closing each of the compartments. Suitable handles 16 are secured to each of

the doors 14 adjacent their lower ends, whereby they may be swung upwardly upon the hinges to give access to the compartments.

5 A pair of ears 17 are formed on the lower end of each of the doors 14 and have pivotally secured thereto, rods 17' which depend downwardly within each of the compartments and have their lower ends forked 10 to form a pair of relatively spaced arms 18. The arms 18 are provided with their ends bent inwardly and rounded as illustrated at 19 for gripping the bottom of the lowermost bottle in the series which are arranged 15 in each of the compartments. The upwardly inclined rear wall 11 of the storage compartment is provided with an offset portion 19' at its lower end to form a recess 20 within the storage compartment, whereby 20 a space is provided to allow the inwardly bent ends of the arms 18 to engage the bottom of the lowermost bottle of the series.

In operation, a plurality of bottles are arranged in each of the compartments one 25 above the other and by closing the doors 14 to the compartments, the arms 18 will slide over the sides of the lowermost bottles of the series in each compartment and engage the bottom thereof within the recess 20 and 30 by opening any one of the doors, the lowermost bottle of the series in the respective compartment to the door will be withdrawn to a point adjacent the outer end of the inclined wall 10, obviating the necessity of a 35 person placing his hand within the water within the storage chamber to withdraw the bottle. As the lowermost bottle of each of the series is withdrawn, the next adjacent bottle moves downwardly into an engagement 40 with the inclined wall 10 and by closing the door to the respective compartment, the arms again engage the bottom of the lowermost bottle, thus positioning the device ready to withdraw the next bottle.

45 From the foregoing description taken in connection with the accompanying drawing, it will be noted that bottles containing beverages of various kinds may be separated and stored in different compartments, the 50 doors to the different compartments being labeled to indicate the kinds of beverages contained therein, and by lifting upwardly upon the desired door, the desired bottle containing the desired beverage will be withdrawn, obviating the necessity of withdrawing several bottles before the correct 55 beverage can be obtained.

While I have shown and described the preferred embodiment of my invention, it 60 will be understood that minor changes in construction, combination and arrangement of parts may be made without departing from the spirit and scope of the invention as claimed.

Having thus described my invention, what 65 I claim is:

1. An ice box provided with an article storage chamber having an opening, a movable door for closing said opening, and means pivoted to the door for an engagement with the article when the door is closed, said means carrying the article to a point near said opening when the door is opened.

2. An ice box provided with an article storage chamber having an opening, a movable door for closing said opening, a grab pivoted to said door and extending within the chamber for gripping the article when the door is closed, said grab carrying the 80 article to a point in said opening when the door is opened.

3. An ice box provided with an article storage chamber, vertically extending partitions formed in said chamber to provide a 85 plurality of compartments, movable doors for closing said compartments, grabs pivoted to each of said doors and extending into the compartments for clamping an article, said grabs carrying the articles to a 90 point near said opening when the doors are opened.

4. An ice box comprising an ice chamber, an upwardly inclined rear wall secured to the rear wall of the ice box, said ice box 95 provided with an opening, a downwardly inclined wall connected to the lower end of the upwardly inclined wall forming an article storage chamber, a plurality of vertical walls within the storage chamber providing a plurality of compartments, doors hinged to the ice box and engaging the outer end of the downwardly inclined wall, grabs pivotally secured to the lower end of the doors and extending into the compartments for an 100 engagement with the article, said grabs carrying the article to a point near said opening when the doors are opened.

5. An ice box comprising an ice chamber, a storage chamber, vertical walls formed in the storage chamber providing a plurality of compartments, doors hinged to the ice box and closing the opening in the storage chamber, rods hinged to the doors and extending into the compartments of the storage chamber, a pair of relatively spaced arms formed on the free ends of each of the rods and adapted to grip an article, said rods carrying the article to a point near said opening when the doors are opened.

6. An ice box comprising an ice chamber, a storage chamber, vertical walls formed in the storage chamber providing a plurality of compartments, doors hinged to the ice box and closing the opening in the storage chamber, rods hinged to the doors and extending into the compartments of the storage chamber, a pair of relatively spaced

arms formed on the free end of each of the rods and adapted to grip an article, said rods carrying the article to a point near said opening when the door is open, and an offset portion formed in the compartments to form recesses to permit the rods to engage in rear of the article.

In testimony whereof I affix my signature in presence of two witnesses.

WILLIAM E. JAMES.
